CLAIM

The ornamental design for a 3-way electrical tap, as shown and described.

DESCRIPTION

FIG. 1 is a front top perspective view of a 3-way electrical tap, showing my new design;

FIG. 2 is a front elevational view thereof;

FIG. 3 is a back elevational view thereof;

FIG. 4 is a left elevational view thereof;

FIG. 5 is a right elevational view thereof;

FIG. 6 is a top plan view thereof; and,

FIG. 7 is a bottom plan view thereof.

The prongs, openings, and certain portions of the body of the 3-way electrical tap shown in broken lines are unclaimed subject matter and form no part of the claimed design.

1 Claim, 5 Drawing Sheets# US D955,993 S
